UNITED STATES PATENT OFFICE.

HERBERT E. RIDER, OF NEW YORK, N. Y., ASSIGNOR TO CELINDA P. ROBINSON, OF SAME PLACE.

ENVELOP-OPENING APPARATUS.

SPECIFICATION forming part of Letters Patent No. 594,650, dated November 30, 1897.

Application filed July 17, 1896. Serial No. 599,486. (No model.)

To all whom it may concern:

Be it known that I, HERBERT E. RIDER, a citizen of the United States, and a resident of the city of New York, county and State of 5 New York, have invented certain new and useful Improvements in Envelop - Opening Apparatus, of which the following is a specification, reference being had to the accompanying drawings, forming part hereof.

10 This invention relates to apparatus for opening envelopes, and has for its object to provide a device which will be set into action by contact of an envelop therewith and which will operate when thus set into action to cut 15 or shear a narrow strip from the end of the envelop, thereby opening said end of the envelop, so that the letter or other contents of the envelop may be removed therefrom.

According to my invention a movable plat- 20 form is provided adapted to be moved by contact of the envelop therewith, and a shearing or cutting device operates in proximity to said platform and is adapted to shear or cut a narrow strip from an envelop in contact with 25 said platform, and a motor is constructed to actuate said shearing device to cut or shear the strip from the end of the envelop, and this motor is set into action by the movement of said platform. The mechanism is designed 30 to perform a single cutting or shearing operation for every actuation of the movable platform, and to that end is so constructed that the movable platform returns to normal position upon being relieved of the pressure of 35 the envelop, as by the cutting off of the end of the envelop, and the return of the platform to normal position puts the mechanism in position to check the movement of the shearing or cutting device upon the completion of an 40 operation thereof.

My invention includes various improvements in construction, all of which will now be fully described in connection with the accompanying drawings.

45 The drawings represent an envelop-opening apparatus embodying my invention.

Figure 1 is a perspective view of the complete apparatus. Fig. 2 shows a vertical longitudinal central section of the casing with 50 the interior mechanism in full. Fig. 3 is a

transverse vertical section of the apparatus on the line 3 3, Fig. 2. Fig. 4 is a detached plan view of a portion of the cutters.

The various working parts are shown as in- 55 closed within a casing or box *a*, said casing or box being adapted to rest upon a flat surface, as of a desk or table. As shown, this casing is open at the bottom, but it may of course be closed, and the sides of the casing are inclined upward and inward, and the cas- 60 ing has a flat top, but may of course be of any suitable shape. The flat top of the casing has a slit or opening *a'* formed therein, said slit or opening being of sufficient width and length to permit the entrance of the end 65 of an envelop therein, but preferably to prevent any possibility of injury to the user, not being wide enough to admit the fingers of the user.

The cutters or knives are arranged so as to 70 act upon an envelop inserted through the slit or opening *a'*, and in the construction shown one of these cutters is fixed and the other mov- 75 able, the fixed cutter *b* being shown as part of a frame *c*, secured at the under surface of the top piece of the casing *a*, said frame providing bearings for the several operating-shafts to be hereinafter described, and the movable cutter *d* is shown as held in a pivoted swinging frame, comprising a rock-shaft *e*, having bear- 80 ings in said fixed frame *c*, said rock-shaft having upwardly-extending arms *e'* carrying said cutter and a downwardly-extending actuating-arm *e''*, shown as carrying a roller *e'''*, actu- 85 ated by a cam, as will be hereinafter de- 90 scribed. The fixed frame *c* is shown as com- 95 prising a horizontal portion held against the lower face of the top plate of the casing *a* and of two vertical portions extending downwardly therefrom at either end thereof. The cutting edge or cutter *b* is shown as formed upon the horizontal portion of the frame *c*, but may be a separate piece attached thereto, if de- 100 sired. The movable cutter *d* is shown as se- cured by screws to the upwardly-extending arms *e'* of the pivoted frame, but may be formed integrally with said arms, if desired.

The two cutting edges are shown arranged so as to approach each other at an inclination, so that the shearing or cutting action is con-

centrated upon one point at a time, said cutting-point rapidly moving from end to end of the article acted upon, and thus a gradual shearing action is obtained.

5 For the actuation of the cutting edges I provide a motor, shown as a coiled spring or clock-spring *f*, said coiled spring secured to the frame and to a winding-shaft *f'* and said winding-shaft *f'* having a pawl-and-ratchet 10 connection with a gear-wheel *g* and said gear-wheel *g* meshing into a pinion *g'* on a shaft *h*, fitted to rotate in bearings in the frame *c*, whereby the spring as it unwinds causes said shaft *h* to rotate. The end of the winding- 15 shaft *f'* of the clock-spring *f* is shown as squared for engagement with a winding-key. The construction and operation of spring-motors are well understood, and the construction here shown need not be particularly described, and it is of course evident that spring-motors of other construction than that shown and that other motors than spring-motors may be employed.

The effect of the motor connection of the 20 shaft *h* is to continually tend to rotate said shaft *h*, and this tendency is normally restrained and the shaft thus normally held at rest by a detent *i*, shown as secured upon said shaft *h* and bearing against a trip-lever *j*, and 25 this trip-lever *j* is connected to a movable platform *k*, said movable platform *k* being arranged in proximity to the cutting edges and shown as just below these edges and being movable to a distance from the line of cutting 30 about equivalent to the width of the narrow strip to be secured or cut off from the end of the envelop, and this movable platform is shown as pivoted at one end, the left-hand end in Fig. 2, to the frame *c* and as supported 35 at the other end by a light spring *l*, said spring *l* surrounding a fixed pin *l'*, which forms a stop to the downward movement of the platform *k*.

The spring *l* is a yielding device which tends 40 to hold the movable platform in its upper position, as shown, but when the end of an envelop is inserted through the slit *a'* and is pressed downward upon the movable platform *k* this platform is moved to lower position, compressing the spring *l* and coming to 45 rest against the stop *l'*. When the envelop has thus moved the platform *k* downward and is in contact with said platform, a narrow portion of the end of the envelop lies between said platform and the line of cut, and 50 it is now only necessary to actuate the cutters to insure the cutting off of this narrow strip.

The trip-lever *j* above referred to is shown 55 as pivotally connected at its upper end to a lug extending downwardly from the movable platform *k* and as guided at its lower end by passing through an opening in a bracket, said bracket extending downwardly from the top plate of the casing.

The trip-lever *j* is provided with notches 60 in its edges, so formed that when the trip-lever is in lower position, to which position it is moved by the depression of the movable

platform *k*, resulting from the contact of an envelop with said platform, said trip-lever permits the detent *i* and the shaft *h*, to which 70 said detent is secured, to freely rotate without interference from said trip-lever, but when said trip-lever is in normal upper position, as shown, said detent is held by the trip-lever in the position shown, or if the detent 75 is in motion the detent is stopped when it reaches the point in its revolution at which it is shown. Thus the depression of the movable platform *k* causes the detent to be released, and thereby permits the detent and 80 its shaft *h* to be actuated by the motor or sets the motor into action, and the detent and shaft having been thus released will move freely and rapidly through one revolution without restraint by the trip-lever, but will 85 be stopped at the completion of one revolution if before or at the completion of such revolution the platform *k* and trip-lever have returned to normal positions.

The actuation of the movable cutting edge 90 or cutter *d* through the rotation of the shaft *h* is accomplished by the cam *n*, secured upon said shaft *h*, and against which cam works a cam-roller *e*, fitted to rotate freely on a pin projecting from the downwardly-extending 95 arm *e'* of the pivoted frame carrying said movable cutter *d*. The cam-roller *e* is held against the surface of said cam *n* by a suitable retracting device, such as the spring *o*, shown as encircling the rock-shaft *e* at the 100 left-hand end of said shaft and secured at one end to the frame *c* and bearing at the other end against one of the upwardly-extending arms *e'* of said rock-shaft *e*. During one complete rotation of the shaft *h* the cam *n* 105 will cause the movable cutter *d* to move in shearing contact with the fixed cutter *b* to perform one complete shearing or cutting operation and will permit the spring *c* to return said movable cutter to the normal position shown in the drawings. A cushion or 110 buffer *m* is shown as secured upon the bracket *m* in position to receive the impact of the movable cutter when the cutter returns to normal position, and thus to prevent undue 115 noise from the operation of the apparatus, but this buffer may be omitted, if desired. It is of course evident that other actuating means than the cam shown may be employed 120 for causing the rotative movement of the shaft *h* to actuate the movable cutter within the purview of my invention, but the means above described insure an effective and rapid operation.

The operation of my improved apparatus 125 will be readily understood. Normally all parts are at rest; but the motor if wound or charged continually tends to actuate the apparatus. When the end of an envelop is inserted through the slit *a'* and pressed downward upon 130 the movable platform *k*, the downward movement of the platform actuates the trip-lever *j* to release the detent *i*, and thus permits the motor to rotate the shaft *h*, and the cam *n* on

the shaft *h* actuates the pivoted frame carrying the movable cutter *d* and causes one complete shearing operation of the cutters, as above described, and when the narrow strip 5 is severed or cut off from the end of the envelop this narrow strip is also pushed in front of the movable cutter *d*, and an apron or guide *p* may be provided to prevent these cuttings from falling upon the working parts, and at 10 the completion of the shearing operation the portion of the end of the envelop which was in contact with the movable platform has been removed from above said platform and said platform has been permitted to return to normal 15 position, and the trip-lever *j* is in position to stop the detent at the completion of one revolution of the detent and cam.

The operation of the cutters is practically instantaneous, and the cutting operation is 20 completed within the first half-revolution of the shaft *h*, and the cutter returns to normal position during the second half-revolution of the shaft *h*. Thus the operation of cutting off the end of the envelop is performed automatically and takes place at once upon the depression of the movable platform *k*, and the 25 sides of the envelops may be cut off as rapidly as they are inserted through the slit *a'*.

It is evident that various modifications may be made in the construction above particularly described, and shown in the drawings. I do not, therefore, limit my invention to such specific construction but

What I claim, and desire to secure by Letters Patent, is—

In an apparatus for opening envelopes, the combination with the casing *a* having the opening *a'* therein adapted to receive the end of an envelop, of the pivoted movable platform *k*, and sustaining-spring *l* and stop *l'*, the fixed 40 cutting edge *b*, the rock-shaft *e*, carrying the movable cutting edge *d*, and spring *o* tending to hold said rock-shaft in normal position, the shaft *h* actuated by a motor and provided with a detent *i*, the trip-lever *j* connected to 45 the movable platform *k*, and the cam *n* on the shaft *h*, said cam actuating the rock-shaft *e* and movable knife carried by said rock-shaft, substantially as set forth.

Signed at New York, in the county of New 50 York and State of New York, this 14th day of July, A. D. 1896.
